CLAIM

The ornamental design for a firearm recoil buffer spring assembly, as shown and described.

DESCRIPTION

FIG. 1 is a front, right perspective view of a firearm recoil buffer spring assembly.

FIG. 2 is a right side elevation view of the firearm recoil buffer spring assembly of FIG. 1.

FIG. 3 is a left side elevation view of the firearm recoil buffer spring assembly of FIG. 1.

FIG. 4 is a top plan view of the firearms recoil buffer spring assembly of FIG. 1.

FIG. 5 is a bottom plan view of the firearm recoil buffer spring assembly of FIG. 1.

FIG. 6 is an enlarged front elevation view of the firearm recoil buffer spring assembly of FIG. 1.

FIG. 7 is an enlarged rear elevation view of the firearms recoil buffer spring assembly of FIG. 1.

FIG. 8 is a rear, left, and bottom perspective view of the firearm recoil buffer spring assembly of FIG. 1; and,

FIG. 9 is a rear, right, top perspective view of the firearm recoil buffer spring assembly of FIG. 1.

The broken lines and the areas within them depict portions of the firearm recoil buffer spring assembly that form no part of the claim. The outermost broken line in FIGS. 1 and 6 and the innermost broken line in FIGS. 7, 8, and 9 depict boundaries of the claim and form no part thereof.

1 Claim, 6 Drawing Sheets
